UNITED STATES PATENT OFFICE.

ANDREW CLELAND, OF TORONTO, CANADA.

PNEUMATIC SADDLE FOR CYCLES.

SPECIFICATION forming part of Letters Patent No. 583,209, dated May 25, 1897.

Application filed June 14, 1895. Serial No. 552,814. (No model.) Patented in Canada March 9, 1895, No. 48,393.

To all whom it may concern:

Be it known that I, ANDREW CLELAND, of the city of Toronto, in the county of York, in the Province of Ontario, Canada, have invented certain new and useful Improvements in Pneumatic Saddles for Cycles, of which the following is a specification.

This invention has been patented to me in Canada on the 9th day of March, 1895, No. 48,393.

My invention relates to improvements in pneumatic cycle-saddles; and the object of the invention is to provide a simple form of pneumatic saddle on which the rider may not only be comfortably but most firmly held in the easiest position on the seat; and it consists, essentially, of providing a central depression extending from the front of the saddle rearwardly and having two obliquely-extending rearward depressions forming a continuation of the central depression and extending laterally from the same, the central depressions being preferably provided with openings throughout for the purpose of ventilation, and the saddle being otherwise constructed, as hereinafter more particularly explained.

The figure represents a plan view of the saddle.

In the drawing like letters of reference indicate corresponding parts.

The pneumatic side portions of the front of the saddle are represented at A, between which extends rearwardly the perforated depression B. The rear portion of said depression is divided into two laterally-extending branches B² B², thus forming the raised portion A², into which and the side portions the branches B² B² gradually merge.

In a saddle such as described the rearward lateral branches of the central depression serve to enable the rider to assume his proper position on the saddle as the tuberosity of the ischium fit into these extensions, and by reason of the raised side portions and the portion A² the rider is effectually prevented from sliding off.

I claim—

In a pneumatic bicycle-saddle, the combination with the side pneumatic cushions and rear cushions forming a continuation of the same on the same level, of the central depression having oblique rearwardly-extending depressions from the rear of such depression, the ends of which are inclined and merge into the top of the saddle, so as to form a forwardly-extending central raised portion, as and for the purpose specified.

ANDREW CLELAND.
